TUBING CLAMP

George Coanda, North Hollywood, and Roger A. Ekbom,
La Crescenta, Calif., assignors to Pharmaseal Labora-
tories, Glendale, Calif., a corporation of California

Filed July 1, 1963, Ser. No. 75,606

Term of patent 14 years

(Cl. D54—13)

FIG. 1.

FIG. 2.

FIG. 3.

FIG. 4.

FIG. 5.

FIG. 6.

FIGURE 1 is a top plan view of a tubing clamp, showing our new design;

FIGURE 2 is a front elevational view thereof;

FIGURE 3 is an end elevational view thereof, viewed from the left end of FIGURE 1;

FIGURE 4 is an end elevational view thereof, viewed from the right end of FIGURE 1;

FIGURE 5 is a cross-sectional view on the line 5—5 of FIGURE 1;

FIGURE 6 is a cross-sectional view on the line 6—6 of FIGURE 1; and

FIGURE 7 is a perspective view thereof.

We claim:

The ornamental design for a tubing clamp, as shown.
